VERTICALLY ADJUSTABLE TABLE

Paul Lazard, Luxemburg, Luxemburg

Application April 5, 1946, Serial No. 659,787
In France January 22, 1948Section 1, Public Law 690, August 8, 1948
Patent expires January 22, 1965

3 Claims. (Cl. 311—39)

1

The object of my invention is a convertible table adapted to be adjusted in height to form, selectively, a low table or a regular table.

It has been proposed before to hide the more or less unsightly adjustment means of such tables by a frame fixedly attached to the table top. Such a frame, however, is most objectionable in tables with extension leaves as used for increasing the area of the table top, since the frame interferes with the manipulation and movements of said extension leaves.

My invention avoids this drawback by providing means for adjusting such a frame vertically relative to said top so that in the high position of the top the frame can be lowered to permit free movement of the extension leaves, whereas in the low position of the top the frame can be raised so as to hide not only all the adjustment means, but also the narrow circumferential surfaces of the then superposed extension leaves.

In a preferred embodiment of my invention the means for adjusting the height of the table are coupled with the means for adjusting the frame relative to the table top so that by the operation of the former means the latter means are automatically operated in desirable manner.

It is a further object of my invention to provide in convertible tables with extension leaves means whereby the leaves and frame are automatically positioned for extension when the table top is adjusted to its high position, and the frame and leaves are automatically retracted from the first position when the table top is adjusted to its low position.

Other features and advantages of my invention will appear from the following specification in connection with the accompanying drawings showing some embodiments of the invention by way of example.

In these drawings:

Figures 1 and 2 are longitudinal vertical sections through a table in accordance with the invention and showing the table in its "high" and "low" positions, respectively;

Figure 3 is a corresponding sectional end view of the table in its "high" position;

Figure 4 is a similar view of a modification with the frame in its low position relative to the extension leaves;

Figure 4A is a partial sectional view, on a larger scale, of the embodiment of Figure 4 with the frame in its high position relative to the extension leaves;

Figure 5 shows in vertical section an arrangement applicable to the modification shown in Figure 4;

Figure 6 shows a modified form of construction of the uprights;

Figure 7 is a plan view showing a table with extension leaves displaced automatically during

2

the downward and upward movements of the table, the center plate of table top being omitted.

Figure 8 shows, in vertical section, a mechanical detail forming part of the system shown in Figure 7.

In the example shown in Figures 1 and 3 the table comprises a base plate 1 forming a support and provided with legs 2 which may be either straight or curved depending upon the particular period style adopted. The table could, for example, comprise either a single central leg or two or four straight legs as shown or curved legs. Hinged to this base plate on transverse axes are the tiltable uprights or links 3—4 which, thus, are interposed between the aforesaid base plate and the table top. In the example shown this top, composed of the two superimposed panels or plates 5, 5', is supported in its lower position by an independent frame 6 constituting a railing inside of which both the flat top and the uprights are concealed in the "low" position (Figure 2).

The uprights support the frame 6 for example by rollers 7 pivoted to the uprights and adapted to roll in the longitudinal grooves 8 provided on the inner face of the frame 6.

Thus, on lifting the frame 6, the uprights are brought to the vertical position during which movement, as may be seen from the dotted lines in Figure 1, the rollers 7 move in the grooves 8. The uprights, in their vertical position, i. e. the "high" position of Figure 1, may be immobilized by any suitable locking system. The uprights carry at their upper ends the rollers 9 which, on approaching the "high" position, lift the top relatively to the frame and thus make possible the extension of the leaves constituted by the two parts 5, 5' of the top. For obtaining these relative adjustments the rollers 7 are not only located closer to the pivoted i. e. lower ends of the uprights than the rollers 9 but are also offset laterally relative to the rollers 9, as shown.

In the example shown in Figure 4 the tiltable uprights 3, 4 provide a direct support for the panel 11 which, in turn, supports the table top, for which purpose the rollers 12 of the uprights travel in the grooves 13 provided in said panel while the frame 14 is adapted to be adjusted to two different levels relative to the panel 11 with which it is connected by a system of tenons and mortises 10 which allow limited vertical sliding movement of the frame while, by means of a system of latches or spring controlled sliding bolts, one can immobilize the frame 14 relative to the panel 11 in the "high" position of said frame. Under these conditions the table can be adjusted in the following three positions:

(1) "Low" position with the extension leaves concealed;

(2) "High" position with the extension leaves concealed;

(3) "High" position with the extension leaves spread out.

According to Figure 4A spring pressed bolts i. e. snap bolts 100 with calote-shaped heads 101 engage into calote-shaped sockets 102 of the frame 14. Vertical downward pressure on the frame 14 disengages the bolt head 101 from the socket 102 and lowers the frame 14 from the "high" position of Figure 4A in which it overlaps the extension leaves to the "low" position of Figure 4.

The return of the frame 14 to the "high" position relative to the panel 11 can be brought about automatically at the end of the downward movement of the top as shown in Figure 5. For this purpose the extensions 15 of the tiltable uprights 3 and 4 when the latter are being lowered can be made to abut against lugs 16 of the narrow sides of the frame 14, thereby lifting the latter.

Instead of using rigid tiltable uprights, as shown in Figure 6, uprights made of two parts 17, 18 may be used, which are connected by means of the hinges 19. This figure shows an intermediate position clearly illustrating the collapsing of these uprights. Springs and locking means associated with the hinges or directly with the uprights can be provided for ensuring the rigidity of the uprights while they occupy their vertical position and hold the table top in the latter's "high" position.

In the example shown in Figure 7 in plan view (with the top 5 omitted) and shown in detail in Figure 8, (the top being broken away to expose the frame) the tiltable upright 3 is connected by means of the iron bracket 23 to the articulation 21 provided with two vertical rollers 12 and supporting a horizontal wheel 20 which moves along the channel 8 by which the Italian style extension leaves 5, 5' are supported on the articulation 21. The wheel 20 mounted in the track 22 which is mounted slantwise beneath the extension leaf 5 urges the latter to move away from the center or closer to it, respectively, during the movements of the tiltable upright 3 during which movements the table is thus simultaneously raised or lowered. The automatic displacement of the extension leaves and frame relatively to each other could be brought about by other means than the sliding means and a system of articulated rods or levers may be used, as will be understood by the skilled worker.

It will be understood that my invention is not limited to the examples described above, and that many structural modifications can be devised without departing from the scope of the invention. The shapes of the various structural elements of the table can be varied in conformity with particular stylistic requirements. On the other hand the materials used for the panel, base and other parts of the table may be greatly diversified. For example, wood, metal, plate glass, plastics, etc., or any combination of materials, as well as any decorative materials, may be used.

What I claim is:

1. A table the top of which is adjustable from the height of a low table to the height of a regular table, said table comprising, in combination, a base of substantially the height of said low table, a top comprising two connected extension leaves, a frame normally surrounding the edges of said top only when the leaves are not extended, means for adjusting said top to said two mentioned heights comprising a pair of uprights hinged adjacent the ends of said base for folding

movement to and from each other on said base, a slide guide on said frame, runner connections on the upper ends of said uprights slidable in said guide, and extensions on the upper ends of said uprights on which said leaves rest, whereby the top is moved vertically relatively to said frame to a position above the frame as the uprights are moved to vertical position to permit extension of the leaves.

- 10 2. A table having a top adjustable from the height of a low table to the height of a regular table comprising, in combination, a base, legs to support the base at the height of a low table to form with said table top a low table, uprights pivotally mounted at the ends of the base for movement between a vertical position and a position above and substantially parallel to the base, each of said uprights having a length such as to support said top at a regular table height when positioned substantially vertically, but movable from said vertical position substantially in parallelism with the base to leave the top superimposed on said base in the low table position, guides on the top, means on the upper ends of the uprights slidable and rotatable in said guides to permit movement of the uprights to the positions aforesaid, and means for limiting the tilting movement of the uprights to the vertical position aforesaid.
- 15 30 3. A table having a top member adjustable from the height of a low table to the height of a regular table comprising, in combination, a base member, legs to support the base at the height of a low table to form with said table top member a low table, uprights having sets of connecting means at their ends and connections between the ends of the uprights and each of the said members, one set of connections for the uprights being pivotally mounted adjacent the ends of one of the said members for movement between a vertical position and a position above and substantially parallel to the base member, each of said uprights having a length such as to support said top member at a regular table height when positioned substantially vertically, but movable from said vertical position substantially in parallelism with the base member to leave the top member superimposed on said base member in the low table position, guides on the other of said members, the other set of connections of the uprights being slidable and rotatable in said guides to permit movement of the uprights to the positions aforesaid, and means for limiting the tilting movement of the uprights to the vertical position aforesaid.
